UNITED STATES PATENT OFFICE.

CARL M. JENSEN, OF LEWISTOWN, MONTANA, ASSIGNOR OF ONE-HALF TO SAMUEL C. DITTY, OF LEWISTOWN, MONTANA.

DAMPER.

1,163,929.

Specification of Letters Patent. Patented Dec. 14, 1915.

Application filed February 11, 1915. Serial No. 7,611.

To all whom it may concern:

Be it known that I, CARL M. JENSEN, a citizen of the United States, residing at Lewistown, in the county of Fergus and State of Montana, have invented certain new and useful Improvements in Dampers; and I do declare the following to be a full, clear, and exact description of the invention, such as will enable others skilled in the art to 10 which it appertains to make and use the same.

My invention relates broadly to improvements in dampers and more particularly to those adapted for use in chimneys or flues.

15 The object of the invention is to provide a device of this character formed of a plurality of pivotally supported plates adapted to overlap each other at their edges to check the upward draft within the chimney, and 20 to provide stops whereby the edges of said plates are prevented from moving into air tight contact.

With the above object in view, the invention resides in certain novel features of construction and combination hereinafter more fully described and claimed and shown in the drawings wherein:

Figure 1 is a vertical transverse section through a fire place and a portion of the 30 flue leading upwardly therefrom; Fig. 2 is a vertical section as seen along the plane of the line 2—2 of Fig. 1, the damper plates being shown in inactive position; Fig. 3 is a view similar to Fig. 2 but illustrating said 35 plates in active position; Fig. 4 is a horizontal section as seen along the plane indicated by the line 4—4 of Fig. 1; and Fig. 5 is a perspective view of one of the damper plates.

40 In these drawings, constituting a part of the application, a fire place P is shown as having its rear side formed by an upwardly and forwardly curving wall W, the latter projecting a slight distance into the enlarged 45 lower end E of a flue F, said enlarged end and the remainder of the flue being here shown as connected by a contracted throat T.

Disposed in the space between the front wall of the enlarged end E of the flue, and 50 the projecting upper end of the rear wall W of the fire place P, is a rectangular supporting frame 1, this frame comprising a pair of parallel horizontally disposed side bars 2 which are constructed of angle iron, the 55 horizontal flanges of which project out-

wardly, and a pair of transverse angle iron end bars 3 which connect the opposite ends of the side bars 2 and whose horizontal flanges likewise project outwardly. In applying the frame to use, the 60 horizontal flanges of the end bars 3 are embedded in the side walls of the lower end E of the flue F, as disclosed at 4 in Fig. 2, the horizontal flange of the front side bar is embedded in the front wall of said lower end 65 as indicated at 5 in Fig. 1, and as seen at 6 in Fig. 1, the horizontal flange of the rear side bar is partially embedded in the projecting upper end of the rear wall W of the fire place P. By so positioning this frame, the 70 chimney construction is effectively reinforced and the frame is rigidly secured in position.

Disposed transversely between the two longitudinally extending side bars 1, is a 75 plurality of parallel damper plates 10, these plates being of rectangular construction as most clearly seen in Figs. 1 and 5. The lower corners of the plates 10 are provided with integral pivot studs 11 which project 80 horizontally therefrom through openings 12 in the upright flanges of the side bars 1, whereby the various damper plates are pivotally supported to swing upwardly to the position seen in Fig. 2, or downwardly to 85 that seen in Fig. 3, such swinging of all of the plates being effected simultaneously by the provision of a longitudinally extending spacing rod 20 which passes through perforated ears 21 formed on the upper edges of 90 the various plates 10, said rod being prevented from shifting within the openings of said ears by extending a plurality of transverse pins 20' through the rod on opposite sides of the ears, this construction being 95 most clearly disclosed in Fig. 4.

With the parts constructed and arranged as above described, the numerous plates 10 are adapted to fold downwardly to check the upward draft through the chimney, but it becomes expedient to provide means whereby such plates are prevented from moving into air tight contact. For this purpose, each of the plates 10 is provided with an integral laterally projecting stop finger 25 at one of its upper corners, these 100 fingers being preferably offset from the plane of the plates as shown, whereby when the plates are folded downwardly as seen in Fig. 3, the stop fingers 25 will abut the up- 105 110

per edge of one of the side bars 1, thus correctly spacing the edges of the various plates, in order to allow the necessary draft and smoke to pass upwardly therethrough. 5 Particular emphasis is laid upon the fact that the plates 10, the pivot studs 11 thereon, the stop fingers 25, and the perforated ears 21 are all struck from single sheets of metal, this being very simple yet efficient 10 construction.

In connection with the parts so far described, I intend to provide means whereby the position of the various damper plates 10 may be varied from the exterior of the 15 chimney, and, as typical of one form of such means, I have shown a chain 30 connected at its inner end to the rod 20, the outer end of said chain being equipped with a weight 31, while its intermediate portion 20 passes through an opening in one wall of the chimney and is trained over a pulley or other appropriate guide 33. By the provision of this chain and weight, the latter will 25 counter-balance the weight of the various plates 10 and will retain them in the positions to which they are adjusted.

From the foregoing description, taken in connection with the accompanying drawings, it will be seen that although a very 30 simply constructed damper has been provided for carrying out the object of the invention, such damper will be very efficient in operation and may not be closed to such an extent as to entirely prevent upward 35 draft through the chimney, it being therefore practically impossible for smoke to be expelled from the front of the fire place P.

I claim:—

1. A damper comprising an open horizontal rectangular frame having a series of 40

aligned openings in its opposite side bars near the upper edges thereof, a plurality of substantially rectangular plates having aligned integral pivot studs projecting longitudinally from the lower corners thereof 45 and pivotally mounted in said openings, said plates being positioned to overlie each other at their edges, ears extending transversely from the upper edges of said plates midway their lengths and having aligned openings elongated transversely of said plates, integral stop fingers projecting longitudinally from one of the upper corners of said plates and having their free ends offset laterally and positioned for engagement with the upper edge of one side bar of the frame, whereby to prevent the edge portions of said plates from coming into air tight contact, an operating rod passing through the aligned openings in said plates, 60 and a plurality of pins extending transversely through said rod on opposite sides of said ears to prevent said rod from shifting within said openings.

2. The combination with a damper comprising a plurality of pivotally mounted damper plates adapted to move in unison, of ears projecting from one edge of said plates and having openings elongated transversely of said plates, a single operating rod 65 passed through all of the openings, and stop pins passed through said rod on opposite sides of the ears.

In testimony whereof I have hereunto set my hand in presence of two subscribing witnesses. 75

CARL M. JENSEN.
